UNITED STATES PATENT OFFICE.

PAUL H. SCHMELZER, OF ST. LOUIS, MISSOURI, ASSIGNOR TO P. C. MURPHY TRUNK COMPANY, OF ST. LOUIS, MISSOURI, A CORPORATION OF MISSOURI.

TRUNK-TRAY.

1,017,812.

Specification of Letters Patent.

Patented Feb. 20, 1912.

Application filed May 29, 1911. Serial No. 630,168.

To all whom it may concern:

Be it known that I, PAUL H. SCHMELZER, a citizen of the United States, residing at St. Louis, Missouri, have invented a certain 5 new and useful Improvement in Trunk-Trays, of which the following is a full, clear, and exact description, such as will enable others skilled in the art to which it appertains to make and use the same.

10 This invention relates to trunk trays.

One object of the invention is to provide an inexpensive trunk tray having adjustable partitions of novel construction which can be removed or arranged in operative position 15 quickly and easily.

Another object is to provide a trunk tray which is so constructed that it can be repaired cheaply in case the partitions thereof become broken or displaced. And still another object is to provide a trunk tray having partitions which securely tie the sides and the ends of the tray together.

20 Other objects and desirable features of my invention will be hereinafter pointed out.

25 Figure 1 of the drawings is a perspective view of a trunk tray constructed in accordance with my invention; Fig. 2 is an enlarged perspective view illustrating the means that holds the partitions in position; 30 and Fig. 3 is a horizontal sectional view which also illustrates the construction of said means.

Referring to the drawings which illustrate the preferred form of my invention, 35 1 designates the ends of a trunk tray, and 2 the sides of the tray which are connected together in any suitable manner, the tray herein shown being provided with angle-shaped corner-pieces 3 that are secured to

40 the ends and sides of the tray, as shown in Fig. 1. The tray is provided with a center partition 4 and a plurality of cross partitions 5 which are connected together and also to the sides and ends of the tray by 45 means of novel construction. In the preferred form of my invention as herein shown, said means consists of substantially T-shaped heads A on the outer ends of the center partition and cross partitions which

50 fit in correspondingly-shaped sockets B on the ends and sides of the tray, respectively, the inner ends of the cross partitions 4 also being provided with T-shaped heads A that fit in correspondingly-shaped sockets B

formed in the center partition 4. Each of 55 the heads A preferably consists of a strip or plate of metal bent or doubled in the manner shown in Figs. 2 and 3 so as to form a head 6 and a pair of laterally projecting flanges 7 arranged at approximately 60 right angles to the head 6 so as to embrace the partition to which the device is connected. Fastening devices 8 which pass through said flanges 7 and through the partition, secure the head A to the partition, 65 and the pair of flanges 7 are contracted or drawn together at a point adjacent the heads 6 so as to form a reduced shank or neck 9. Each of the sockets B is formed by a pair of vertically disposed plates 10 spaced away 70 from each other, as shown in Fig. 2, so as to form a slot 11, and bent or offset slightly at 12 so as to form a socket which corresponds to the dimensions of the heads 6 on the partition, the plates 10 being retained in position by means of fastening devices 13.

When the partitions are arranged in operative position, as shown in Fig. 1, the heads 6 on the ends of the partitions lie behind the plates 10, as shown in Fig. 3, and 80 thus securely tie the sides of the tray to the center partition 4 whose ends are tied to the ends 1 of the tray. The partitions can be removed easily by merely moving them vertically so as to withdraw the heads A from 85 the sockets B, and in case the partitions become broken it is a very simple matter to repair the tray because the means which retains the partitions in position consists of sheet metal devices that are detachably connected to the partitions and to the sides and ends of the tray.

90 The fabric C that forms the bottom of the tray and which covers the sides and ends of the tray hides the plates 10 from view, and the partitions are also provided with a suitable covering that hides the portion of the flanges 7 which embrace the partitions, thus producing a neat construction and one which does not comprise corner-blocks arranged at 95 the intersection of the center and cross partitions and at the points where said partitions join the ends and sides of the tray.

100 Having thus described my invention, what I claim as new and desire to secure by Letters Patent is:

In a trunk tray, a pair of vertically disposed metal plates connected to one of the

vertical walls of the tray and spaced slightly away from each other so as to form a vertical slot, the edge portions of said plates adjacent said slot being bent laterally away from the vertical wall of the tray so as to form a pocket, a partition, and a T-shaped device on the end of the partition whose head lies in said pocket, said device having a contracted neck which lies in said slot

and laterally projecting flanges which embrace the partition.

In testimony whereof I hereunto affix my signature in the presence of two witnesses, this twenty fourth day of May 1911.

PAUL H. SCHMELZER.
